(57) **CLAIM**

The ornamental design for a reversible floor mat, as shown.

DESCRIPTION

FIG. 1 is a top, front, left-side perspective view of a reversible floor mat.

FIG. 2 is a top plan view thereof, the bottom view being a mirror image.

FIG. 3 is a front elevation view thereof, the rear elevation view being a mirror image.

FIG. 4 is a left-side elevation view thereof, the right-side elevation view being a mirror view; and,

FIG. 5 is a top plan view thereof, shown in a position of use, the bottom view being a mirror image.

The broken lines shown in FIG. 5 depict the environment in which the design resides; and form no part of the claim.

1 Claim, 3 Drawing Sheets(56)
